(74) Attorney, Agent, or Firm—Marshall, Gerstein & Borun LLP

(57) **CLAIM**

The ornamental design for a “glass,” as shown and described.

DESCRIPTION

FIG. 1 is a front elevational view of a glass showing our new design;

FIG. 2 is a right elevational view of the glass of FIG. 1; FIG. 3 is a left elevational view of the glass of FIG. 1; and, FIG. 4 is a rear elevational view of the glass of FIG. 1. The dashed lines are for illustrative purposes only and form no part of the claimed design.

1 Claim, 2 Drawing Sheets**FIG. 1**

FIG. 2
